UNITED STATES PATENT OFFICE.

EDWARD F. HAMILL, OF CHICAGO, ILLINOIS, ASSIGNOR TO THE CHICAGO SIGNAL COMPANY, OF CHICAGO, ILLINOIS, A CORPORATION OF ILLINOIS.

SWITCHING DEVICE.

Application filed May 22, 1919. Serial No. 299,058.

To all whom it may concern:

Be it known that I, EDWARD F. HAMILL, a citizen of the United States, residing at Chicago, in the county of Cook and State 5 of Illinois, have invented a certain new and useful Improvement in Switching Devices, of which the following is a full, clear, concise, and exact description, reference being had to the accompanying drawings, forming 10 a part of this specification.

My invention relates to switching devices and has to do more particularly with so-called silent signal devices useful particularly in hospitals or places where silent call 15 signals are to be sent. One of the features of my invention is the provision of a portable or removable signal controlling mechanism and enclosure adapted for insertion and removal from a wall socket so that this 20 portion of the device may be moved from room to room, thereby requiring fewer devices than where each room is so equipped. Another feature of my invention is an improved contact controlling means whereby 25 the contact operating slide is set by a push button and then released by the operation of a push button controlled electro-magnet. Another feature of my invention is the provision of visible indicating means in the 30 form of a small lamp adapted to show the actuation of the device for further signaling. There are other features of my invention which will be more particularly pointed out in the ensuing specification and claims.

Referring now to the accompanying drawings:

Fig. 1 is a perspective view of my invention;

Fig. 2 is a wall receptacle or terminal 40 block;

Fig. 3 is a view of the mechanism mounting showing the terminals on the rear side thereof adapted for insertion in the wall block terminals;

Fig. 4 is a vertical cross section through the center of the device as shown along the line 4—4 in Fig. 7;

Fig. 5 is an interior view showing the contact slide and cooperating contacts;

Fig. 6 is a partial sectional view along the line of 6—6 of Fig. 7, showing the construction of the push button cord terminal or binding post;

Fig. 7 is a front view of the device with

the cap and part of the framework cut 55 away;

Fig. 8 is a sectional view along the line 8—8 of Fig. 7;

Fig. 9 is a perspective view of the slide operating push button and its cooperating 60 electro-magnet;

Fig. 10 is a partial sectional view of the mechanism mounting and one of the terminal plugs carried thereby; and

Fig. 11 is a circuit diagram showing the 65 switch mechanism connected in the controlling circuit.

Referring first in a general way to the operation and use of the switch mechanism in connection with a lamp signal system for 70 hospitals the device may be placed in one of the rooms with the push button at the end of the cord in reach of the patient. In order to call an attendant the calling push button is operated thereby closing a circuit 75 for a latch controlling magnet which releases the contact operating slide to close circuits so as to operate a local signal lamp inside the switch mechanism and one or more lights at distant points in order to call 80 the nurse or other attendant. When the call is responded to, the signal may be effaced by pushing the small push button on top of the switch device to reset the contact operating mechanism and efface the local signal 85 lamp in the device to show that it has been reset for further actuation, and efface the distant signals.

Referring now more particularly to the detailed construction of the mechanism, I 90 provide a base 15 preferably made of insulating material and in which suitable terminal plugs 16, 17, 18, 19 and 20 are embedded these terminals being split so as to yieldingly engage corresponding receptacles 21, 22, 23, 24 and 25 in the wall terminal mounting block 26. This wall block 26 is provided with suitable ears 27, 28 so that it may be attached to usual wall box and then covered with a wall plate 29. The wall terminals 21 100 to 25 are provided with suitable connectors to which the circuit conductors may be connected.

Now as to the portable or removable portion of the switch mechanism, this is carried 105 by the base 15 and includes a contact operating element in the form of a slide 30 attached to the base by a screw 31 and signal

plug nut 32 which is threaded upon the central terminal plug 19. By means of this connection at the nut 32, slide 30 is in electrical connection with the post 19. This contact 5 operating slide 30 and its cooperating contacts 33, 34, 35 and 36 is shown in its actuated or signal sending position in Fig. 5, the same mechanism being diagrammatically illustrated in its normal or non-signal sending position in Fig. 11. Contact 33 is electrically connected with the terminal plug 16 and contact 34 is electrically connected with the terminal plug 17. Terminal plug 20 is wired to a stud 37, which is embedded in base 15 and electrically connected to the push button cord terminal 38 as shown more clearly in Fig. 6. A similar cord terminal 39 is provided at the opposite side of the downwardly projecting lug 15^a on the base 15 so as to 20 take the other cord conductor. This terminal binding post 39 is connected to a corresponding stud 40 which is connected to one terminal of the contact slide controlling magnet 41, while the other terminal of this 25 magnet is connected to the contact 35, which is normally in electrical connection with the slide 30. A push button 42 and two conductor cord 43 are connected across the binding posts 38, 39, leading to the terminal studs 30 37, 40 so that the operation of push button 42 will close the circuit through release magnet 41 to permit actuation of the contact operating slide 30.

In order to control the contact operating 35 slide 30 I preferably connect it to a sliding shaft 45 by means of a laterally extending stud 46 which is staked in the shaft 45 and has a reduced end projecting loosely into the opening 47 of the slide 30. A spring 48 encircles the lower end of the shaft 45 tending to press this shaft upwardly so as to effect a signal sending operation thereof when the armature 49 carried by the electro-magnet 41 withdraws the latch 50 from the 40 shouldered stop 51 on the shaft 45. Such operation of the shaft 45 also moves the contact operating slide 30 to its signal sending 45 position as shown in Figs. 9 and 11. This slide 50 it will be noted has cut away portions along its two side edges positioned so as to make and break with the various contacts according to the position of the slide. The slide controlling shaft 45 carries an actuating button 52 at its upper end for the purpose of resetting the mechanism after it has 55 been actuated and the attendant has responded to the call.

As previously pointed out, when the push 60 button 42 is operated to extend a call the mechanism in the switch is operated by means of the magnet 41. This switch mechanism is preferably manually reset and in order to indicate the condition of the switch 65 mechanism I provide a signal in the form of a small lamp 53 which is carried in a lamp

jack including contact springs 54, 55, jack springs 54 being in electrical contact with the slide controlled contact 36, while the other jack spring 55 is in electrical contact with the terminal screw 56, which is electrically connected by means of a conductor 57 with the cord terminal stud 37. Thus when the contact slide 30 is in its normal or inoperative position the signal lamp 53 is effaced, but when the slide has been moved to its alternative position when the cord push button 42 is operated the lamp 53 is caused to glow. A resetting of the mechanism by means of the resetting button 52 effaces the signal 53 so as to indicate that the switch device is ready for another call.

In order to suitably protect the switch device, I provide a casing 59 adapted to be secured to the switch frame by means of two small screws 60. In the face of this casing 85 or cap 59, I provide a small bull's-eye 61 through which the light from the signal lamp 53 may be seen; this bull's-eye being of a suitable transparent material, preferably of glass. Although the calling device is shown 90 in connection with a particular call or signal system, it is to be understood that it is not limited to use with any particular circuit. Extra terminals may also be readily supplied, such as the terminal plug 18 and its 95 receptacles 23 which are not used in the particular circuit illustrated.

In Fig. 11, I have shown diagrammatically a signal system in which the switching device is connected. The parts 100 being numbered to correspond with the reference characters of the switch as already described. In the installation of the device 105 wall sockets such as are shown in Fig. 2 are installed in the various rooms current 110 from a main source 63, 64, being connected to the terminals 24, 25, and thus to the terminal plugs 19, 20. At a distant room, such as the nurse's or other attendant's quarters 115 an annunciator is installed having suitable signals preferably in the form of lamps 65, each one of which is individual to a particular room or calling station. Each signal 120 65 is connected by means of a conductor 66 to the wall terminal 21 and thus to the 115 switch plug 16. Thus when the contact slide 30 is actuated, contacts 30, 33 are closed to establish a circuit for the signal 65 from the negative conductor 63 of the battery through the lamp 65, contacts 33, 30 and 120 conductor 67 to the positive conductor. This closing of contacts 30, 33 also establishes a circuit for the room door light 68, which may be placed outside of each room 125 so as to indicate that a call has been made therefrom. A pilot light 69 is also provided and may be placed at the supervisor's desk or other point, this light being connected in circuit over the common pilot wire 70 each time a call is made from any of the switch- 130

ing devices. This pilot light 69 thus remains actuated so long as there is an unanswered call in any room. The annunciator is also preferably provided with a pilot 5 signal 71 which is operated from the common pilot wire 70 so as to indicate that a call has been made. This is particularly useful should any of the individual call signals be out of order and fail to operate.

10 As to the circuit for supervisor's pilot light 69 and the circuit for annunciator pilot signal 71, these may be readily traced. As to lamp 69 this is lighted when the contact 34 and slide 30 are closed, the circuit 15 being traced from power conductor 63, through lamp 69, common pilot conductor 70, contact 34, slide 30 and conductor 67 to the other power conductor which is numbered 64. The circuit for annunciator pilot 20 lamp 71 is also closed when the contact 34 and slide 30 are connected, the circuit for pilot 71 being traced from power conductor 63, through the second vertically extending conductor from the left, lamp 71, conductor 25 70, contact 34, slide 30, and conductor 67 to the other power conductor.

Referring now to the operation of the system as shown in Fig. 11 should a patient or other party in any room desire to call a nurse, attendant or other party according to the use of the system, cord push button 42 is operated to establish a circuit for magnet 41 which attracts its armature and permits the operation of contact slide 30 by the 35 spring 48. A circuit is thus closed for the local indicating lamp 53 by means of contacts 30, 36. The operation of the slide 30 automatically interrupts the circuit for magnet 41 so that although the push button 40 42 be maintained closed current does not continue to flow through magnet 41, thereby reducing the current consumption to a minimum. The operation of the contact slide 30 also closes a circuit for the corresponding call signal 65 by means of contact 45 33, this also lighting the room door light 68 which may be placed immediately outside the room, as in the corridor, so that an attendant knows that a call has been 50 transmitted from that station. The supervisor's pilot lamp 69 is also operated over the common pilot wire 70 by the closing of switch contact 34.

When the attendant answers the call the 55 reset button 52 is immediately operated so as to notify the supervisor and others that that particular call has been answered. The operation of this button 52 resets the slide 30 so as to lock beneath the socket latch, 60 also interrupting the circuits for the various signals. The calling device is now ready for extending another call.

I claim:

1. In a device for operating a plurality of 65 signal circuits, a base, a single elongated me-

tallic contact plate longitudinally slidably carried on said base, said plate having a plurality of cut away portions in each of the side edges thereof, a pair of said cut away portions being transversely aligned and the 70 others being out of alignment, transversely aligned signal circuit contacts carried by the base extending transversely of said plate, a spring pressed latch for holding said contact plate with the transversely aligned cut 75 away portions thereof aligned with said transversely aligned contacts, spring means for urging said plate toward a position with said last mentioned contacts and cut away portions out of alignment to close said signal 80 circuits, and electromagnetic means for releasing said latch to close said signal circuits.

2. In a device for operating a plurality of 85 signal circuits, a base, a single elongated metallic contact plate longitudinally slidably carried on said base, said plate having a plurality of cut away portions in each of the side edges thereof, a pair of said cut away portions being transversely aligned and the 90 others being out of alignment, transversely aligned signal circuit contacts carried by the base extending transversely of said plate, a spring pressed latch for holding said contact plate with the transversely aligned cut 95 away portions thereof aligned with said transversely aligned contacts, spring means for urging said plate toward a position with said last mentioned contacts and cut away portions out of alignment to close said signal 100 circuits, and electromagnetic means for releasing said latch to close said signal circuits, one of said cut away portions being arranged relative to one of said contacts so that the circuit of said electromagnetic 105 means is interrupted when said plate is moved to position to close the signal circuits.

3. In a signalling device of the character described, a plurality of signal controlling contacts, a movable contact member, spring 110 means urging said movable contact member into position to engage said contacts, a latch for holding said contact member against movement due to the action of said spring means, an electromagnet for actuating said 115 latch to release said movable contact member, a contact independent of said signal controlling contacts for controlling said electromagnet, said movable contact member normally engaging said magnet controlling contact but being out of engagement therewith when moved to signal contact engaging position, and a visible signal controlled by one of said signal controlling contacts to indicate the position of said movable contact member.

4. In a signalling device of the character described, a base, an elongated contact making slide of conducting material carried on said base having a plurality of cut away 130

portions in each of the side edges thereof, a pair of said cut away portions being in transverse alignment and the others being out of transverse alignment, and trans-
versely aligned pairs of contacts carried by the base extending transversely of said slide and adapted to make and break connection with the slide adjacent the side edges thereof.

5. In a signaling device of the character described, a base, an elongated contact making slide of conducting material carried on said base having a plurality of cut away portions in each of the side edges thereof, a pair of said cut away portions being in transverse alignment and the others being

out of transverse alignment, transversely aligned pairs of contacts carried by the base extending transversely of said slide and adapted to make and break connection with the slide adjacent the side edges 20 thereof, and a spring pressed detent for holding the slide against actuation carried by said base in front of the slide and contacts, said magnet operating said detent to prevent actuation of the slide and co-operating contacts.

In witness whereof, I hereunto subscribe my name this 2nd day of May, A. D. 1919.

EDWARD F. HAMILL.
